UNITED STATES PATENT OFFICE.

JAMES C. WARD, OF NEW YORK, N. Y.

EXTENDIBLE WINGS.

1,324,218.

Specification of Letters Patent.

Patented Dec. 9, 1919.

Application filed March 19, 1918. Serial No. 223,275.

To all whom it may concern:

Be it known that I, JAMES C. WARD, a citizen of the United States, residing at New York, in the county and State of New York, have invented certain new and useful Improvements in Extendible Wings; and I do hereby declare the following to be a full, clear, and exact description of the invention, such as will enable others skilled in the art 10 to which it appertains to make and use the same.

My present invention relates to apparatus for producing upon the stage the effect of wings on the human form whose peculiarity 15 is that they can be spread or folded at will, and be made virtually to appear or disappear. By the use of this apparatus a variety of surprising effects, beautiful or grotesque, may be produced, thereby contributing to the variety and charm of spectacular stage productions. It is a special advantage of my improved apparatus that it gives the actor who wears it the free use of his hands, except for the few moments which 25 it takes to spread or fold up the wings.

I have illustrated my invention in a preferred form in the accompanying drawings wherein Figure 1 is a perspective view thereof with the wings folded or dropped, 30 Fig. 2 is a rear elevation of the apparatus with the wings spread, Fig. 3 is a plan view of a single section of a preferred form of wing and Fig. 4 is a horizontal section of the back plates which form the support and brace for the wing sections.

The harness which fits the actor or actress and furnishes the points of attachment for the wings and auxiliary parts may take a variety of forms, but I prefer to employ an upper belt 10 which is worn just under the arms, and a lower belt 11, worn around the waist. This latter belt is preferably held down so as the better to resist the tension to which it is subjected by means of straps 12, 45 passing under the groin of the wearer. Similarly I prefer to provide shoulder straps 13, attached to the upper belt 10.

The support proper for the wings is carried by the upper belt and preferably comprises the foundation plate 14 within the belt, and the carrying plates 15 riveted or bolted to the plate 14 through the belt and carried on the back or outer surface of the belt. I prefer to provide a padding 16 of 50 felt or similar material inside of the founda-

tion plate 14 to protect the wearer's back. In the preferred form shown, the carrying plates are fastened by butterfly nuts 17, or other easily manipulated devices, so that said plates may be readily removed from 60 their foundation, when desired, carrying the wings with them.

The outer parts of both carrying plates are inclined backward away from the body, and each inclined part carries a pivot or pin 65 18 upon each of which one wing is pivotally suspended.

The wings may be made in various forms and may be variously constructed without departing from my invention. I prefer 70 however to form these wings, as shown, of separate narrow sections 19, pivoted on the pins 18, over each other. These sections can be given a great variety of fanciful shapes and colors to produce all sorts of effects. 75

The wing sections 19 are connected, each to its neighbor, by tapes or strings 20, 21, so that, if the foremost of the series be lifted or swung upward on the common pivot it will draw the next section after it. This second 80 section draws the third, and so on, until the entire wing is spread, as shown in Fig. 2. This effect is preferably produced by means of cords 22. These pass first through loops 23 on the posts 24 attached to the plates 15, 85 and then through guides 25. At the ends of the cords 22 are rings 26. By pulling down on the cords 22 as they hang down in front of him, the wearer can raise the wings, and by slipping the rings 26 over hooks 27 on the 90 lower belt 11, as in Fig. 2, he can secure the wings in this outspread condition, leaving the hands free. When the rings are again removed from the hooks the wings may be allowed to fold up by their own weight in 95 the position shown in Fig. 1.

My invention may be embodied in a great variety of modified forms without departing from the scope of my claims, and I do not limit myself to the details herein shown and 100 described.

What I claim is—

1. In apparatus of the class described, a harness for the body composed of an upper belt and a lower belt, wings pivotally supported on the back of the upper belt, and means including fastening devices on the lower belt for raising and lowering the wings, said means extending within reach of 105 the wearer. 110

2. Apparatus of the character described in claim 1 hereof, wherein the upper belt has shoulder straps and the lower belt is provided with straps adapted to pass under the body of the wearer.

3. In apparatus of the class described, a belt, a foundation plate, carrying plates hav-

ing posts provided with guides, wings pivotally suspended on the carrying plates, and cords attached to the wings passed through said guides.

In testimony whereof I affix my signature.

JAMES C. WARD.
